TROUSERS

Seth Adamson, Larchmont, N. Y., assignor to
United States Rubber Products, Inc., New York,
N. Y., a corporation of Delaware

Application May 16, 1935, Serial No. 21,826

3 Claims. (Cl. 2—237)

This invention relates to improvements in the construction of the waist embracing portion of trousers.

It is now customary to employ either a belt or suspenders to hold trousers up in place about the waist of the wearer.

One object of the present invention is to construct the waist embracing portion of trousers so that this portion will conform better to the 10 anatomy of the wearer above the hips, and remain comfortably in place without requiring either a belt or suspenders to hold the trousers up.

Another object is to provide the waist embracing portion of the trousers with a frusto-conical 15 shape to better conform to the tapered contour of that portion of the human body lying between the top of the hip bones and the lowest ribs.

Another object is to construct both the waist band portion of the trousers and the strip of 20 stiffening material secured to the inner face thereof of elastic material adapted to yieldingly grip the body of the wearer to hold the trousers up and at the same time provide a comfortable fit that will readily accommodate muscular movement 25 at the waist line.

A further object is to construct the waist band portion of the trousers of elastic material having secured thereto a combined waist band stiffening element and lining in the form of a single thickness strip, to thereby avoid the use of both a 30 canvas lining strip and curtain at the inner face of trousers as has been customary heretofore.

Still a further object of the invention is to provide the waist band portion of the trousers 35 with a stiffening element consisting of a fashioned strip of elastic webbing that has an articulate curvature in the direction of its length and is adapted to assume a frusto-conical shape when placed about the body of a person.

The above and other objects of the invention 40 will be more fully understood when read in connection with the accompanying drawings illustrating one good practical form thereof.

In the drawings:

Fig. 1 is a front view of the upper portion of a 45 pair of trousers constructed in accordance with the present invention;

Fig. 2 is a face view of a strip of elastic fabric fashioned with a lengthwise curvature;

Fig. 3 is a view similar to Fig. 1, the fly of the trousers being open to show the inner face of the trousers;

Fig. 4 on a larger scale is a section taken on line 4—4 of Fig. 3;

Fig. 5 is a front perspective view showing the

trousers of Fig. 1 as being worn, the contour of the body of the wearer being indicated in dot-and-dash lines, and

Fig. 6 is a view of a modification of the construction shown in Fig. 2.

The present invention is applicable to various forms of trousers of the full length or knicker type and is concerned only with the upper or waist embracing portion of the trousers, but it is particularly well adapted for use in connection 10 with trousers which are made of a one-way stretch woven fabric having small elastic threads placed at intervals in the weave to impart a small amount of stretch to the fabric in the body and leg encircling direction.

Referring to the drawings, a pair of trousers 15 of conventional appearance is illustrated as having the waist embracing portion thereof constructed in accordance with the present invention. The outer waist band portion 11 in the 20 construction shown is formed of a separate piece of material from the main portion of the trousers 10 and the portions 10 and 11 are secured together by the stitching 12 as is usual. However, if desired the portions 10 and 11 of the trousers 25 may be formed as an integral unit, as is frequently done in the conventional type of trousers.

The present invention contemplates that the waist band portion 11 instead of having the usual cylindrical shape when embracing the body of the 30 wearer, shall have the frusto-conical shape clearly shown in Fig. 5 to thereby better conform to the tapered contour of the portion of the body of the wearer above the hips.

The human body of the average male adult is 35 so formed that there is a space of approximately three inches between the top of the hip bone x and the end of the lowest rib y which is not protected by any bone structure. In this space are found thick muscular layers strengthened by 40 sheets of fibrous tissue. The waist w of the average male adult who is not over normal weight-tapers inwardly slightly from adjacent the hip bones to a point adjacent the lower ends of the ribs y as indicated in dotted lines in Fig. 5, and 45 by giving the waist embracing portion of the trousers the frusto-conical shape shown they will better conform to the contour of the waist of the average person and will remain up in place better.

Since, as above stated, there is a space of approximately 50 three inches between the top of the hip bone x and end of the rib y that is not protected by bone but is provided with thick muscular layers, it is proposed to utilize practically this entire space to support the weight of the 55

trousers, and to this end the waist band portion 11 and inner waist band stiffening 13, to be described, are each made considerably wider than the waist band portion and waist band stiffening element commonly employed heretofore.

The waist embracing portion of trousers as commonly constructed heretofore has been provided with a stiffening fabric of canvas or buckram secured to the inner face of the trouser forming material, and over the stiffening element has been sewed a curtain of lining material. The cutting of these two strips and securing them together and then in place in the trousers involves considerable work and expense.

One object of the present invention therefore, is to provide a single elastic strip 13 that will take the place of the waist band stiffening element and curtain employed heretofore, and since the waist embracing portion of the trousers in accordance with the present invention is given a frusto-conical shape, it is important that the elastic strip 13 which serves as a combined stiffening strip and lining shall have a similar frusto-conical shape.

This is accomplished in accordance with the present invention by fashioning the stiffening strip 13 so that it has the arcuate curvature best shown in Fig. 2. The desired curvature may be imparted to the strip 13 as it is woven by employing elastic warps 14 the tension of which gradually increases in the direction of greatest curvature. That is, the warps 14 under the greatest tension will lie at the upper curved edge of the strip 13 and those under the least tension will lie near the lower curved edge. The elastic warps 14 are preferably omitted from a narrow marginal portion 15 along the lower edge of the strip 13 so that binding stitches passed through this portion 15 will not injure any elastic warps. When the curved stiffening strip 13 is placed around the body of the wearer its lower edge will obviously form a circle of greater diameter than its upper edge and this will cause the strip to assume the form of a frustum of a cone which is desired.

The elastic stiffening strip 13 is preferably long enough to reach around the inner face of the waist band portion 11 and its upper edge is sewed to the upper edge of the portion 11 preferably by a folded-in seam 16, as clearly shown in Fig. 4. The lower edge of the strip 13 does not need to be sewed to the fabric 10 or 11 but the rear pockets 17 may be sewed to the lower edge portion 15 of this strip as at 18, to support the pockets from this strip and the strip may be secured to the rear seam portion of the trousers at 19. The ends of the strip 13 may be secured to the front portion of the trousers adjacent the fly flaps at 20, and the fly 21 may have the usual buttons 22.

It will be seen from the foregoing that by employing the single stiffening strip 13 of elastic material in place of the curtain and stiffening strip used heretofore, considerable saving in work and material is secured and a very simple and satisfactory construction is provided.

The strip 13, waist band portion 11 and trousers forming material 10 are all preferably formed of a one-way-stretch elastic fabric adapted to yield in the body encircling direction, and by making the portion 11 and strip 13 elastic; that is of fabrics employing elastic threads in their construction, they will not only contract and expand to embrace the body of the wearer

snugly and comfortably, but will also contract and expand together so that neither one will cause the other to pucker. While it is desirable that the fabric 10, as well as the parts 11 and 13 shall be elastic, this is not essential, for since the lower edge of the strip 13 stretches less than its upper edge, fairly satisfactory results can be obtained by securing the lower edge of the elastic portion 11 and points along the lower edge of the elastic strip 13 to an inelastic fabric 10.

The waist band portion 11 and strip 13 are preferably made approximately two and one-half inches wide to rest upon substantially the entire portion of the waist between the hip bones and ribs. This may increase the height of the trousers slightly over those now in general use. A distinctive feature of the present invention results from the frusto-conical shape given the upper portion of the trousers and is illustrated in Fig. 1 in which the top of the folded trousers forms a distinct arc of a circle. This is caused by flattening out the frusto-conical portion of the trousers.

The employment of an elastic waist band portion 13 having an inherent lengthwise curvature 25 imparted thereto by weaving the elastic warps 14 in the fabric under gradually increasing tension, as above described, not only materially improves the fit of the trousers around the waist, but has the further important result of permitting a substantial stretch at the upper edge of the trousers and a much shorter stretch at the lower edge of the waist band portion. In this manner an elastic waist band stiffening element or portion 13 is secured which will not cause the fabric of the trousers to pucker adjacent the lower edge of said portion 13.

It may be desirable, in many cases, to provide the elastic stiffening strip 13 with both an upper and lower edge portion from which the elastic warps are omitted. A modified construction is therefore shown in Fig. 6 in which the elastic stiffening strip 13a has a lower marginal portion 23 and upper marginal portion 24 from which the elastic warps are omitted. As a result of this modified construction the upper inelastic portion 24 will receive the stitches 16 and the lower inelastic portion 23 will receive the stitches 18, so that the needle inserting these stitches will not strike any elastic warps. When the construction just described is employed it may be desirable to provide one elastic warp thread at the selvage edge of the portions 23 and 24, since in most cases the sewing stitches are not placed close enough to the edge to strike these selvage warps and they impart a contractive action to the inelastic portions 23 and 24.

It will be apparent from the foregoing that trousers constructed in accordance with the present invention will fit the waist of the wearer 60 neatly and snugly throughout a wider area than ordinary trousers, and that the frusto-conical shape given the waist portion of the trousers and contractive force of the elastic strip 13 will both contribute to the support of the trousers so that the wearer will not need either a belt or suspenders to hold them up. Furthermore the wide, snug fitting waist portion of the trousers and elastic action of the waist band will constitute a substantial abdominal support for the wearer.

Having thus described my invention what I claim and desire to protect by Letters Patent is:

1. Trousers constituting an outer garment having an outer waist band portion adapted to stretch in the body encircling direction, an elas-

- tic waist band stiffening element having its upper edge secured to the upper edge of said outer waist band portion and comprising a woven elastic strip secured at the inner face of said outer waist band portion and provided with elastic warps woven under gradually increasing tension to impart a lengthwise curvature to the strip and a greater stretch to the upper edge of said strip than to its lower edge, to thereby provide a maximum range of stretch at the upper edge of the trousers and a smaller range of stretch at the lower edge of the waist band of the trousers whereby puckering of the trouser fabric is avoided.
15. 2. Trousers constituting an outer garment having a waist area of frusto-conical shape and formed of an outer waist band portion adapted to stretch in the body encircling direction, an elastic waist band stiffening element having its upper edge secured to the upper edge of said outer waist band portion and comprising a woven elastic strip secured at the inner face of said outer waist band portion and provided with elastic warps woven under gradually increasing tension to impart to the strip an inherent lengthwise curvature that causes it to take the form of an arc of a circle when the strip lies flat and the form of a frustum of a cone when placed in the body encircling position, and said strip being adapted to impart to the waist area of the trousers a smooth frusto-conical shape and a stretch that increases upwardly from the lower to the upper edge of the strip whereby puckering of the trouser fabric is avoided.
- 5 10 15 20 25
3. Trousers constituting an outer garment having a waist area of frusto-conical shape and provided at said area with an elastic waist band stiffening element comprising a woven elastic strip extending substantially entirely around the waist of the trousers and having elastic warps woven under gradually increasing tension to impart to the strip an inherent lengthwise curvature that causes it to take the form of an arc of a circle when the strip lies flat and the form of a frustum of a cone when placed in the body encircling position, and said strip being adapted to impart to said waist area a smooth frusto-conical shape and a stretch that gradually decreases from the upper edge of said strip downwardly towards its lower edge whereby puckering of the trouser fabric is avoided.
